UNITED STATES PATENT OFFICE.

JOHN SAMUEL, OF MONTREAL, QUEBEC, CANADA, ASSIGNOR TO HENRI BEAUDRY, OF MONTREAL, QUEBEC, CANADA.

BELT ATTACHMENT.

1,251,924.

Specification of Letters Patent.

Patented Jan. 1, 1918.

Application filed December 14, 1914. Serial No. 877,142.

To all whom it may concern:

Be it known that I, JOHN SAMUEL, of the city of Montreal, in the Province of Quebec, Dominion of Canada, a subject of the King 5 of Roumania, have invented certain new and useful Improvements in Belt Attachments; and I do hereby declare that the following is a full, clear, and exact description of the same.

10 My invention relates particularly to the attachments for belts whereby they are retained against vertical displacement, and it has for its object to provide a buckle adapted to perform the dual function of a fastener 15 for a belt and a retainer for the belt preventing vertical displacement.

My invention consists essentially of a buckle for a belt adapted to encircle the body of the wearer to support the trousers 20 and comprises essentially means for fastening the buckle to one end of the belt, means for adjustably fastening the opposite end of the belt thereto and, as a component and integral part, a plate-like member with a 25 hook for preventing vertical displacement of the buckle and consequently the belt from proper trousers supporting position, this hook being formed by a piece of the buckle-hook, which is of plate-like form, partially

30 separated therefrom and offset relatively thereto, the purpose of this hook being that the hook may be inserted into or beneath the usual fastening device for the front of the waist-band of the trousers.

35 For full comprehension, however, of my invention, reference must be had to the accompanying drawings in which similar reference characters indicate the same parts, and wherein—

40 Figure 1 illustrates my improved belt attachment in use;

Fig. 2 is a similar view with the belt unfastened;

Fig. 3 is a rear view of a modified form 45 of the device detached from the belt;

Fig. 4 is a longitudinal sectional view taken on line A A Fig. 3.

The body of the device consists of a tongueless buckle (b) having slotted sides 50 in which slide the ends (c) of the belt gripper, the front having suitable ornamentation and the rear being adapted by a transverse slot (d) or other suitable means, for the attachment of one end of the belt.

According to my invention the rear side 55 of the buckle has a portion struck up from the metal thereof either in the form of a pair of spaced parallel fingers or of a single finger (m), the pair of fingers being united together and to the buckle by a bracing web 60 forming an integral part thereof. In the case of the pair of fingers they are spaced a sufficient distance apart to straddle the shank of a button; and in the case of the single finger (m), it is preferably formed 65 parallel to the longitudinal central plane of the buckle and of flat and comparatively narrow cross-section so as to readily enter the common hook-like catch illustrated in Figs. 1 and 2. Both pairs of fingers and 70 the single finger have their free ends facing toward the end (d) of the buckle at which the belt is connected, in order that the device being first made to engage the shank of the button or other trousers fastener, the tension of the belt when being tightened will be caused to draw the device into effective engagement.

With my improved device the ends of the belt may be connected together and with 80 the assistance of the trousers fastener held against vertical displacement, without the use of any extraneous device.

What I claim is as follows:

1. A belt buckle comprising means for 85 fastening the same to one end of a belt and means adjustably fastening the opposite end of the belt thereto, and the said buckle having as a component part a plate-like member with a hook for the purpose described 90 within the boundaries of the member and formed by a tongue-like piece of the plate partially separated therefrom and offset relatively thereto.

2. A belt buckle comprising means for fastening the same to one end of a belt and means for adjustably fastening the opposite end of the belt thereto, and the said buckle having a plate-like back with a hook for the purpose described within the boundaries of 100 the back and formed from a tongue-like piece of the back partially separated therefrom and offset relatively thereto.

3. A belt buckle comprising means for fastening the same to one end of a belt and 105 means for adjustably fastening the opposite end of the belt thereto, and the said buckle having an integral plate-like member with a

portion of the interior partially separated therefrom and offset relatively thereto in the form of a hook.

4. A garment supporting tongueless sheet-metal belt buckle consisting of a unitary member of box-like form oblong in longitudinal section and adapted to have one end of the belt fastened thereto and the opposite end passed longitudinally therethrough, the 10 sides of the buckle having slots each presenting an edge oblique to the rear side of the buckle, the said rear side extending parallel to the length of the belt, a transverse belt gripper carried loosely within the slots,

and the back of the said box-like member 15 being of plate-like form with a hook adapted to engage a fastening of the garment and consisting of a tongue-like piece partially separated therefrom and offset relatively to the back of the buckle.

20 In testimony whereof I have signed my name to this specification in the presence of two witnesses.

JOHN SAMUEL.
